CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

LOOSE-LEAF BOOK

Application filed October 12, 1927. Serial No. 225,762.

This invention relates to covers for loose-leaf binders such as those of the ring book type, and particularly to those having the back and sides hinged together by hinge members having alternated eyes connected by hinge pins or pintles.

The invention relates in part to means for inserting a metal back plate in a cover back of leather or leather-like material. The insertion of a single back plate in pockets formed by splitting the leather occasions some difficulty, to avoid which my present invention divides the back plate into two plates or sections which are inserted separately into the two opposite pockets and are afterward connected together so as to serve every purpose of a single plate.

Another feature of the invention applies to hinge plates which are inserted within the pockets formed in the back or sides (or both) of the book cover, whereby the hinge eyes are effectually concealed.

Figure 1 of the accompanying drawings is a sectional perspective view of a portion of the back and adjacent portions of the sides of a loose-leaf book cover, one of the sides being shown disconnected or unhinged.

Fig. 2 is an elevation of the inner side of the back partly broken away in section.

Fig. 3 is a similar elevation of the adjacent portion of one of the cover sides.

Fig. 4 is a perspective view of the inner back plate or spring plate of the usual loose-leaf ring mechanism.

Fig. 5 is a similar view of a modified form of spring plate.

Fig. 6 is a perspective view of two segmental stiffening plates or hinge plates adapted for use with the inner plate shown in Fig. 5.

In the drawings, the loose-leaf binding mechanism, which may be of the customary ring type or of any other known character, is not shown. The drawing shows the book back B, to the inner side of which is attached a metal plate A which may be the usual back plate or binding plate to which the metal base of the ring binder mechanism may be attached, or this plate may be itself the spring back plate of such loose-leaf ring mechanism.

The sides of the book cover, lettered C C, are hinged to the back by means of a hinge construction having alternating hinge eyes connected by hinge pins or pintles D.

In the construction shown in Figs. 1 and 2, the cover back B has an inner metal plate E embedded within the leather. According to the present construction this plate is divided (preferably down the middle) into two plates or plate sections E and E'. These are inserted into pockets formed by first grooving the inner side of the leather, and afterward cutting or dividing the leather from the middle groove in opposite directions toward the outer edges of the back. This mode of forming pockets in a leather back for receiving a metal plate is set forth in detail in my application No. 100,566, filed April 8, 1926, as applied to a cover having a back and sides of one integral piece of leather reduced in thickness to form flexible hinge portions at the junction of the sides and back. In a later application, No. 120,053, filed July 2, 1926, a similar construction is shown, except that the cover back and sides are non-integral, being of separate pieces of leather, and are hinged together by metal hinges having alternating hinge eyes receiving a single pin or pintle on each side. The leather of the back is here grooved and slotted or divided to form pockets within which to insert the metal plate in the same manner as before, except that at the hinge edges the pockets are cut through to admit the metal hinge eyes which protrude beyond the edge of the leather. Similar metal plates forming hinge members are inserted in similar pockets formed in the cover sides, their eyes protruding beyond the edges of the leather alternating with the eyes of the pocket, so that the respective hinge members may be united by the introduction of the hinge pintles. In the construction shown in said last-named application, the metal plate is inserted edgewise into one of the pockets and the other pocket has its flap cut free and turned up to receive the other half of the hinge plate, and then turned down and cemented against the plate.

According to the present invention, by subdividing the plate to form two plates or

plate sections it is unnecessary to form any flap to gain access to the pocket in the leather. It is sufficient to insert each half or section of the back plate into its own pocket so that 5 when inserted they come together edge to edge. It is then necessary to in some way unite these respective plates or plate sections to each other so that they will serve the same purpose as a single or undivided plate.

10 The plate sections may be thus united in various ways. One suitable and very convenient way is to form them at their adjoining edges with upturned ears *a a* which, passing through suitable slits formed in the inner layer of leather, enter slots *b b* in the inner back plate *A*, and are then turned or clinched down, as shown at *a'* in Fig. 1.

An additional fastening means is also provided by forming the inner plate or plates 20 *E E'* with end prongs or ears *c c* which enter notches *d d* (Fig. 4) formed in each of the ends of the inner plate *A*. These are shown turned in and clinched down upon the plate *A* at the bottom of Fig. 2, and at the top of that 25 figure are shown upstanding as they penetrate the leather, to be bent down when the plate *A* has been superposed.

By thus clinching down the ears *a a* or *c c* (or preferably both) the plates *E E'* are 30 united to each other through the intermediary of the plate *A*. This is the simplest and most readily applied construction. The ears and the slots or notches should fit so closely as to prevent any material lost motion, with 35 the result that the two plates *E E'* function as one.

The hinge plates or leaves *F F* of the cover sides are flat plates introduced into pockets in the material of the sides in similar manner 40 to my said application No. 120,053. The groove *f* first formed in the leather and from which the leather is slitted both ways to form the pocket, may be closed and concealed by cementing in a strip *g* of leather. In the position shown at the right in Fig. 1, the slitting of the leather to form the pocket extends to both sides of this groove, which necessitates that the leather flap *h* shall be cut free at the ends by slits *i* (Fig. 3) to admit the insertion of the metal plate. Or the construction shown at the left in Fig. 1 may be adopted, the groove *f'* being made beyond the plate, 45 so that the slitting to form the pocket is entirely to one side of this groove and the plate may be inserted through the groove and without any slitting of the leather to form a turned up flap.

Figs. 5 and 6 illustrate a modification of the construction shown in Figs. 1 and 2. 50 Here the divided back plate or hinge plate *E E'* has its ears *a a* separated somewhat from the meeting edges of the plates, so that they pass through separated and independent slots *b'* (Fig. 5). The effect is much the 55 same, except that due to the flexure of the

spring plate *A*, the abutting edges of the plates *E E'* move slightly with a flexing movement instead of being held in substantially rigid relation.

Heretofore the hinge eyes *j j'* formed on the hinge members constituting respectively the back plate and the side plates, have projected beyond the leather, thus constituting metal hinges visible at the exterior of the book. Such hinges require to be discolored or otherwise surface treated to avoid too great dissimilarity to the appearance of the exterior leather finish. To avoid this and wholly conceal the hinges I now introduce the hinge eyes within the leather. This requires making the leather wider, so as to extend slightly beyond the hinge eyes in each instance. The leather is cut away between the hinge eyes, but not at the hinge eyes. The result is that when the hinge plates are inserted, their eyes enter the uncut projecting edge portions of the leather. It is desirable to use some cement to fasten these to the hinge eyes, and it is desirable to round the leather to conform it to the hinge eyes. The leather is rounded exteriorly to make a cylindrical finish, as shown in Fig. 1. Thus the portions of leather lettered *k* in Fig. 1 form housings which encircle the hinge eyes and conceal them. These may be rounded by buffing off either before or after the insertion of the hinge plates; or the leather may be wet and the rounding of the portions *k* be accomplished by pressing between dies.

As a modification, instead of taking a thick piece of leather and dividing it, leaving the portions *k* undivided, a thinner piece of leather may be folded around the outside of the plates *E E'* and around the hinge eyes and carried over on the inner or concave faces of the plates, and its edges brought together, or nearly so, at or near the middle line of the inner side of the cover back. The method first described is to be preferred.

While leather is the preferable material for the cover back and sides, yet it is to be understood that any leather-like material or leather substitute which is capable of being split or otherwise treated in the manner described may be substituted and is to be considered an equivalent of leather for the purposes of my present invention.

While the embodiments set forth are deemed preferable, yet it is to be understood that the construction may be modified within the scope of the appended claims.

What I claim is:

1. In a cover for a loose-leaf book of the type having a back and sides hinged together, the cover back, separate hinge plates embedded in the back, each formed with hinge eyes located respectively at the opposite edges of the back, and means for uniting such separate hinge plates so that they serve as a single plate.

2. A cover for a loose-leaf book having a back and sides hinged together, the back and sides having metal plates forming hinge members pocketed within them, and the cover material surrounding and concealing the hinge eyes.
- 5 3. A cover for a loose-leaf book comprising a back and sides of leather-like material, the back and sides having metal hinge plates pocketed within them, with their hinge eyes 10 entering within the edge portions of the material, and the cover material cut out between the hinge eyes of one member to admit the hinge eyes of the connected member, so 15 that the hinge eyes may be brought into axial alignment, and hinge pins entered through the respective hinge eyes.
4. In a cover for a loose-leaf book of the type having a back and sides hinged together, 20 the cover back and sides, hinge plates embedded in the material of the sides, separate hinge plates embedded in the back, each formed with hinge eyes located respectively at the opposite edges of the back, and means 25 for uniting such separate hinge plates so that they serve as a single plate.
5. In a cover for a loose-leaf book of the type having a back and sides hinged together, a back of leather-like material having pock- 30 ets for receiving hinge plates, separate hinge plates in the pockets with their hinge eyes located respectively at the opposite edges of the back, and means for uniting such separate hinge plates so that they serve as a single 35 plate.
6. A cover according to claim 5, said hinge plates meeting adjacent the middle of the back.
7. In a cover for a loose-leaf book of the type having a back and sides hinged together, 40 the cover back having a pocket within it, separate hinge plates in said pocket whereby they are embedded in the back, each formed with hinge eyes located respectively at the opposite edges of the back, an inner back 45 plate applied against the inner side of the back, and means uniting said hinge plates to said inner back plate.
8. A cover according to claim 7, said uniting means comprising turned-up ears with recesses, said ears being turned and clinched down to unite the respective plates.

In witness whereof, I have hereunto signed my name.

CLARENCE D. TRUSSELL.
